UNITED STATES PATENT OFFICE

SÉBASTIEN OTTO ALFRED FIEDLER, OF PARIS, FRANCE, ASSIGNOR TO L'AUXILIAIRE
DES CHEMINS DE FER ET DE L'INDUSTRIE, OF PARIS, FRANCE

FEED WATER HEATER

Application filed July 27, 1928, Serial No. 295,724, and in France June 12, 1928.

The present invention relates to feed water heaters for boilers, and chiefly to feed water heaters, for locomotive boilers, wherein feed water is mixed with heating steam, and it has for its object to provide a feed water heater of this type by which the water will be heated to a temperature exceeding 100° C., that is, a feed water heater operating under pressure, while affording the discharge of all excess of heated water without any loss of steam.

The invention relates more particularly to feed water heaters comprising a mixing chamber which is supplied with water to be heated and with heating steam under a certain pressure, and a distribution chamber, these two chambers being connected together by a water joint.

It has been found that the heating may be materially increased if the water seal is so designed that the mixing chamber will always be practically emptied of water. In these conditions, however, heating steam is liable to proceed into the distribution chamber whence it may escape to the atmosphere.

According to the invention, the mixing chamber and the distribution chamber are both substantially closed and adapted to contain heating steam under pressure, and the portion of the distribution chamber which contains the excess of hot water is provided with any suitable device for discharging the excess of hot water without any loss of steam.

In all cases, use may be made to advantage of a device whose operation is based on the difference of densities between water and steam, and comprising, for example, an obturating member disposed in the water discharge tube and adapted to be subjected, on one face, to a pressure which only depends upon the steam pressure which prevails at each instant in the distribution chamber and, on the opposite face, to a pressure which depends both upon the steam pressure prevailing in said chamber and upon the head of water contained in said tube, whereby said obturating member will close automatically as soon as the level of the water falls below a determined limit.

Further characteristics of the invention

will be specified in the following description, with reference to the appended drawings, which are given only by way of example.

Figs. 1 and 2 are diagrammatical sectional views of two embodiments of the invention.

Fig. 3 is a detail view, in section, of a clack valve.

Fig. 4 shows a modification wherein the valve is constituted by a deformable wall or diaphragm.

The feed water heater shown in Fig. 1 is of the known type where the water to be heated is mixed with the heating steam, as described for example in my prior U. S. patent application No. 275,091 filed May 4, 1928. The said heater comprises two main receptacles 20 and 21, receptacle 20 serving as a mixing chamber, and receptacle 21 as a distribution chamber. Heating steam from conduit 80 is admitted through an oil separator 7 and a nozzle 22 into mixing chamber 20. Chamber 20 may also be supplied at 34 and 35 with exhaust steam from auxiliary machines, such as the air compressor, water pump, or the like. The two chambers are connected together by a bent pipe 25 whose lower end opens into a recess or pocket 19 formed in the bottom of chamber 20.

Hot water is withdrawn from chamber 21 by a pump 27 adapted to force said water through a pipe 28 into the boiler (not shown) and the excess of hot water in chamber 21 overflows into an overflow compartment 29. The two chambers 20 and 21 are provided at the top with respective gas discharge orifices 32, 33 of small size, whereby the gases disengaged from the water by the heating and circulation are discharged without any appreciable loss of heating steam.

The overflow compartment 29 is connected by a U shaped tube 2, 6, to be further described with a tank 30 open to the atmosphere at 13 and which may form part of chamber 21 or may consist of a separate receptacle. Said tank 30 is connected by a discharge pipe 9 with suction vessel 90.

It will be noted that the feed water heater is substantially closed or fluidtight, with the exception of the orifices 32 and 33, through which the loss of steam is negligible. In

these conditions, when the plant is in operation, and as water is heated in chamber 20 by admixture with steam, and collects at the bottom of said chamber and in recess 19, 5 said water will rise in pipe 25 due to the steam pressure and will flow into chamber 21, the pipe 25 forming a water joint between said chambers. The water is withdrawn from the distribution chamber by the hot water pump, and the excess overflows into compartment 29.

As the pressure of the heating steam is comparatively high, means are to be provided for discharging said excess of water 15 into tank 30, open to the atmosphere, without any loss of steam. To this end, use will be made of a balanced valve, as shown in Fig. 1.

In this embodiment of the invention, the 20 liquid discharge tube 2 which opens into the bottom of chamber 21, is provided at its lower part with a small cylinder 4 in which is slidably mounted a piston 5 of suitable weight and forming an obturating member. 25 On the side of said cylinder opens pipe 6 adapted to connect said cylinder with receptacle 30. At the upper part of cylinder 4 opens a tube 3 connected to chamber 21 at a point situated above the uppermost level 30 which may be reached by the water in said chamber.

In these conditions, it will be seen that the opposite faces of piston 5 are subjected to opposite pressures respectively equal to 35 the steam pressure in chamber 1 and to said latter pressure increased by the weight of the water column contained in tube 2. Under the action of the weight of said water column, the piston is raised in the cylinder 40 and sets up the communication between tubes 2 and 6. The water contained at the lower part of compartment 29 is forced or blown off by the steam pressure through tubes 2 and 6 into receptacle 30, whence said liquid 45 is discharged through pipe 9 into suction vessel 90. When the whole excess of water is discharged, its level is considerably lowered in tube 2, whereby the pressure acting on the lower face of piston 5 is much reduced. Hence, piston 5 moves down and cuts off the communication between tubes 2 and 6, whereby the steam filling chamber 21 is 50 prevented from escaping out of said chamber.

55 If water still or again flows into compartment 29, the water level rises in tube 2 and in said chamber, whereby piston 5 is again raised and water again discharged, and so on.

60 Obviously, the diameter of the branch 2 of the U tube may be larger than the diameter of the branch 3, so as to assure a rapid discharge of the water, and the size and weight of the piston are determined in consequence.

65 The use of the balanced valve shown in

Fig. 1 will offer very important advantages as will be now pointed out.

The exhaust steam from the various machines used for the heating of the water will cause violent pulsations in chamber 20. At 70 each pulsation, the heated water which collects in the bottom of said chamber is expelled through pipe 25 into chamber 21, so that the water seal formed by the water contained in this pipe is blown off. Steam thus 75 enters chamber 21 and forces the excess of water through pipe 2, while its pressure assures the filling of the hot water pump cylinders with hot water through tube 26. However, said steam is prevented from escaping 80 to the atmosphere by piston 5 which closes the branch 2 when the excess of hot water has been discharged.

It will be understood that I may thus 85 discharge to the atmosphere the whole amount of water which is not taken up by the hot water pump, irrespectively of the pressure of the heating steam, even if the heating steam is live steam at the boiler pressure, without any detrimental loss of steam.

On the other hand, the water seal formed 90 by the pipe 25 will be blown off at each pulsation of the steam, and without any loss of steam, so that chamber 20 will never contain any appreciable amount of water. The whole capacity of chamber 95 20 is thus free, and may be utilized for the intimate mixing of the cold water and the steam under pressure, and this 100 circumstance is most favourable for the obtaining of the maximum heating; this increase in the heating efficiency has been found in repeated experiments. Further, the resulting temperature remains constant, since 105 it is no longer affected by variations in the amount of water contained in chamber 20, and hence in the volume of said chamber.

110 It should be observed that the diameter of the branch 2 of the U shaped tube shown in Fig. 1 may be selected in such manner as to provide for the discharge of a large excess of water; in this manner, the operation of the device (injector or pump) for the supply of cold water into the heater may 115 be completely independent of the operation of the hot water pump, on the sole condition that the heater shall be supplied with an amount of cold water at least equal to the maximum output of the hot water pump, so 120 that the latter will not fail.

In particular, the cold water pump may be readily replaced by an injector operated by the exhaust steam from the engine, or from an auxiliary engine.

125 Fig. 2 shows a feed water heater which is similar to the preceding, but comprises only a single body or unit 40, and the water seal between the mixing chamber 43 and the distribution chamber 44 consists of two partitions 41—42. Members 70, 71, 72, 73, 74 are 130

exactly similar to members 6, 4, 2, 3, 5 respectively. The heater operates in quite the same manner as the one shown in Fig. 1 and possesses the same advantages.

Piston 5 or the like may be replaced by any other suitable obturating member, and for example by a diaphragm 60, as shown in Fig. 4. Said diaphragm is contained in a chamber 61 and divides the latter into two separate compartments, one of which is connected to tube 2, or 72 and the other to tube 3, or 73. In front of the orifice of tube 6, said diaphragm carries a needle valve 62 or the like, whose displacements are controlled by the deformation of the diaphragm under the effect of the variations in the differential pressure acting on its faces. Obviously, said diaphragm may be replaced by any other suitable deformable wall, aneroid capsule, etc.

In order to obviate the slight trouble in the adjustment of the piston or diaphragm, which might be caused by the accumulation of condensation liquid above piston 5 (Fig. 1) or at one side of diaphragm 60 (Fig. 4), provision may be made of any suitable means for discharging or draining said condensation liquid, automatically or not.

In Fig. 1, it is assumed that said means are simply constituted by an orifice 63, adapted to afford communication between cylinder 4 and the atmosphere. The water collecting in compartment 29 in a continuous manner, piston 5 will normally occupy an elevated position affording communication between tubes 2 and 6. In this position, piston 5 will cover or obturate the discharge orifice 63, thus obviating any loss of steam. If, for any reason, the level of the water falls incidentally in compartment 29, piston 5 will be lowered and will uncover orifice 63 whereby the condensation water will be allowed to escape. It being supposed that the periods during which the level of the water has a tendency to fall in compartment 29 are relatively short, and that orifice 63 has a small diameter, the loss of steam through said orifice will be negligible.

It will be noted that, even if the liquid level in compartment 29 would not fall to a sufficiently low level during a relatively long period, the weight of condensation liquid above piston 5 will, after some time, become sufficient to cause the downward movement of said piston, thus uncovering orifice 63. At this instant, the condensation liquid will be blown off through said orifice and piston 5, immediately relieved from the weight of said condensation water, will automatically resume its normal position.

Obviously, the device for the automatic discharge of the condensation water above described, may be replaced by any other equivalent means. In Fig. 4, it is supposed that said discharge means are simply con-

stituted by a cock 64 adapted to be actuated by hand, directly or through the medium of any suitable transmission means.

As shown in Fig. 3, piston 74 is preferably hollow, and may thus contain a variable 70 charge of lead or the like, by which its weight may be adjusted at will.

Obviously, the invention is not limited to the examples of construction herein described and represented. In Fig. 1, the tank 30 may 75 be entirely distinct from the body 21 of the heater, and may be placed in any desired position relatively to the heater. The U shaped tube may have a more or less open shape, and its branches may have all desired 80 dimensions and shapes. In the different constructions represented, the branch 3 or the like of the U shaped tube may be replaced by a steam pipe opening on the lower face of the piston, the pressure corresponding to 85 the weight of the water contained in said branch being replaced by the pressure of a suitable spring having the proper force and acting upon the said face of the piston. Also, as heating steam, use may be made of exhaust 90 steam from the engine instead of steam from the receiver of a compound machine.

Having now described my invention, what I claim as new and desire to secure by Letters Patent is:

1. A feed water heater for boilers comprising a substantially closed mixing chamber adapted to be supplied with heating steam, means for supplying said mixing chamber with feed water to be heated, a substantially closed distribution chamber, a hydraulic joint between said chambers, the weight of the water column forming said joint being adapted to be overcome by the pressure of the heating steam, whereby water 100 and steam are caused to flow from said mixing chamber into said distribution chamber, said mixing chamber containing substantially no water, means for delivering hot water from said distribution chamber to the boiler 110 feeding means, and steam trap means for discharging any excess of water from said distribution chamber and preventing the escape of steam therefrom.

2. A feed water heater for boilers comprising a substantially closed mixing chamber adapted to be supplied with heating steam, feeding means for supplying said mixing chamber with feed water to be heated, a substantially closed distribution chamber, a hydraulic joint between said chambers, the weight of the water column forming said joint being adapted to be overcome by the pressure of the heating steam, whereby water 120 and steam are caused to flow from said mixing chamber into said distribution chamber, said mixing chamber containing substantially no water, means for delivering hot water from said distribution chamber to the boiler feeding means, an overflow receptacle 125

open to the atmosphere, steam trap means for connecting said distribution chamber with said receptacle and adapted to afford the discharge into the latter of any excess 5 of hot water and to prevent the escape of steam, and means for returning to said feeding means the water contained in said receptacle.

3. A feed water heater for boilers comprising 10 a substantially closed mixing chamber adapted to be supplied with heating steam, means for supplying said mixing chamber with feed water to be heated, a substantially closed distribution chamber, a hydraulic joint 15 between said chambers, the weight of the water column forming said joint being adapted to be overcome by the pressure of the heating steam, whereby water and steam are caused to flow from said mixing chamber into 20 said distribution chamber, said mixing chamber containing substantially no water, a storage compartment in said distributing chamber adapted to receive the water from said mixing chamber, hot water discharge 25 means in said storage compartment, an overflow compartment in said distributing chamber adapted to receive the overflow from said storage compartment, and steam trap means for discharging any excess of water from said 30 overflow compartment while preventing the escape of steam from said distribution chamber.

4. In combination with a feed water heater adapted to be supplied with steam under 35 pressure, discharge means connected with a compartment of said heater for discharging any excess of hot water from said heater and means for controlling the discharge of water through said discharge means, said control 40 means being subjected to the differential action of columns of water and steam whose respective heights depend on the water level in said heater and in said discharge means, whereby said control means are adapted to 45 afford the discharge of water under the pressure of the steam when the water level is above a given level and to cut off said discharge means when the water level is below said given level.

50 5. In combination with a feed water heater adapted to be supplied with steam under pressure, a tube connected with a compartment of said heater for discharging the excess of hot water from said heater, a pressure influenced 55 member in said tube for controlling the discharge of hot water through said tube, one face of said member being subjected to the pressure in said heater increased by the weight of hot water in said tube, and means 60 whereby the other face of said member is subjected to a pressure which is practically dependent on the pressure in said heater only.

6. In combination with a feed water heater adapted to be supplied with steam under pressure, a U-shaped tube, connected with a com-

partment of said heater for discharging any excess of hot water from said heater, one branch of said tube opening into said heater and the other branch opening into said heater at such a level as to be constantly filled with one of the fluids contained in said heater, a pressure influenced member in said tube and whose faces are subjected to the pressures prevailing in said branches respectively, a discharge outlet in said first mentioned branch, adjacent said member, and means, associated with said member for controlling the water discharge through said outlet.

7. In combination with a feed water heater adapted to be supplied with steam under pressure, a U-shaped tube, connected with a compartment of said heater for discharging any excess of hot water from said heater, one branch of said tube opening into said heater and the other opening into said heater at such a level as to be constantly filled with one of the fluids contained in said heater, a piston fitting in said tube in a substantially fluid-tight manner and whose faces are subjected to the pressures prevailing in said branches, respectively, and a discharge outlet in said first mentioned branch, adjacent said piston, whereby said discharge outlet is masked or uncovered by said piston according to the difference of pressure acting upon the faces thereof.

8. A feed water heater comprising a substantially closed mixing chamber adapted to be supplied with heating steam, means for supplying said mixing chamber with feed water to be heated, a substantially closed distribution chamber, a hydraulic joint between said chambers, the weight of the water column forming said joint being adapted to be overcome by the pressure of the heating steam, whereby water and steam are caused to flow from said mixing chamber into said distributing chamber, said mixing chamber containing substantially no water, means for delivering hot water from said distribution chamber to the boiler feeding means, and means for discharging any excess of water from said distribution chamber and preventing the escape of steam, comprising a tube connected with said distribution chamber, a pressure influenced member in said tube for controlling the discharge of hot water through said tube, one face of said member being subjected to the pressure in said heater increased by the weight of hot water in said tube, and means whereby the other face of said member is subjected to a pressure which is practically dependent on the pressure in said heater only.

9. A feed water heater comprising a substantially closed mixing chamber adapted to be supplied with heating steam, means for supplying said mixing chamber with feed water to be heated, a substantially closed distribution chamber, a hydraulic joint between said chambers, the weight of the water column

forming said joint being adapted to be overcome by the pressure of the heating steam, whereby water and steam are caused to flow from said mixing chamber into said distribution chamber, said mixing chamber containing substantially no water, a storage compartment in said distributing chamber adapted to receive the water from said mixing chamber, hot water discharge means in said storage compartment, an overflow compartment in said distributing chamber adapted to receive the overflow from said storage compartment, and means for discharging said overflow from said overflow compartment and preventing the escape of steam, comprising a tube opening at the bottom of said overflow compartment, means for controlling the discharge of water through said tube, a pressure influenced member in said tube and movable with said controlling means, one face of said member being subjected to the pressure in said heater increased by the weight of hot water in said tube, and means whereby the other face of said member is subjected to a pressure which is practically dependent on the pressure in said heater only.

In testimony whereof I have signed my name to this specification.

SEBASTIEN OTTO ALFRED FIEDLER.
